US00D988165S

(12) **United States Design Patent** (10) **Patent No.:** **US D988,165 S**
(45) **Date of Patent:** **** Jun. 6, 2023**

(54) **SAFETY REFLECTOR**

(71) Applicant: **Jiangsu Mingqian Intellectual Property Co., Ltd., Wuxi (CN)**

(72) Inventor: **Guoqing Lu, Wuxi (CN)**

(73) Assignee: **Jiangsu Mingqian Intellectual Property Co., Ltd., Wuxi (CN)**

(**) Term: **15 Years**

(21) Appl. No.: **29/852,691**

(22) Filed: **Sep. 8, 2022**

(51) LOC (14) Cl. **10-05**

(52) U.S. Cl.

USPC **D10/111**

(58) **Field of Classification Search**

USPC **D10/119.1-121, 113.4-114.3, 114.5,**

D10/114.8, 109.1, 120-121, 111

CPC **B62J 6/20; E01F 9/669; E01F 9/619**

See application file for complete search history.

(57) **CLAIM**

The ornamental design for a safety reflector, as shown and described.

DESCRIPTION

FIG. 1 is a front, left and top perspective view of a safety reflector, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1.

The dash-dash broken lines represent portions of the safety reflector that form no part of the claimed design. The dot-dash broken lines indicate enlargements.

1 Claim, 9 Drawing Sheets
